Primary Examiner — Khawaja Anwar*Assistant Examiner* — Mojtaba Tehrani(74) *Attorney, Agent, or Firm* — Tucker Ellis LLP(57) **CLAIM**

The ornamental design for an engine door, as shown and described.

DESCRIPTION

FIG. 1 is a perspective view of an engine door showing our new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken lines and the grayed out portion of the FIGS. 5 and 6 views enclosed by the broken lines depict unclaimed portion of the engine door and form no part of the claimed design.

1 Claim, 2 Drawing Sheets(56)
